(57) **CLAIM**

We claim the ornamental design for the convertible information handling system, as shown and described.

DESCRIPTION

FIG. 1 is a front perspective view of the convertible information handling system in a closed position comprising the present invention;

FIG. 2 is a front side view thereof;

FIG. 3 is a rear side view thereof;

FIG. 4 is a right side view thereof;

FIG. 5 is a left side view thereof;

FIG. 6 is a top view thereof; and

FIG. 7 is a bottom view thereof;

FIG. 8 is a front perspective view in an open position thereof;

FIG. 9 is a front perspective view in a conversion position thereof; and,

FIG. 10 is a front perspective view in a closed tablet position thereof.

Broken lines shown in the drawings illustrate portions of the convertible information handling system, and form no part of the claimed design.
